Attorneys.

UNITED STATES PATENT OFFICE.

PETER J. L. NEMMERS, OF CHICAGO, ILLINOIS.

STERILIZER FOR DENTAL HANDPIECES.

Application filed April 2, 1923. Serial No. 629,267.

To all whom it may concern:

Be it known that I, PETER J. L. NEMMERS, a citizen of the United States, residing at Chicago, in the county of Cook and 5 State of Illinois, have invented a certain new and useful Improvement in Sterilizers for Dental Handpieces, of which the following is a specification.

My invention relates to a sterilizer for 10 dental hand pieces and particularly to a sterilizer for hand pieces for holding the tooth engaging tool or drill piece. It has for one object to provide an inclosure and sterilizer for such hand pieces which are 15 irremovable from the dental engine or which are difficult to remove. Another object is to provide a sterilizer which is adaptable not merely to the irremovable hand piece but to other attachments which may be 20 secured to it, and which may, by the use of my invention, be sterilized without removal. Other objects will appear from time to time in the course of the specification and claims.

I illustrate my invention more or less dia- 25 grammatically in the accompanying drawings wherein:

Figure 1 is a longitudinal section through the sterilizer casing, illustrating it in place; and Figure 2 is a section on the line 2—2 30 of Figure 1.

Like parts are illustrated by like symbols throughout the specification and drawings.

A is a straight shafted dental hand piece adapted to be more or less permanently se- 35 cured to any suitable dental engine, the de- tails of which form no part of the present invention. Shown in dotted lines in Figure 1 is the grinding disc A¹ which may be substituted for the manual drill.

B is a substantially cylindrical shell 40 adapted to inclose said hand piece and pro- vided at its lower end with a removable cap C having thereon a perforated container D adapted to inclose cotton or any other 45 suitable carrying medium which may be impregnated with any suitable disinfectant. The upper end of the cylinder is tapered and reduced, as at E, and is provided with a door F, hinged as at F¹ and provided 50 with any suitable securing snap at F². The door F is illustrated in the drawings as hinged to swing about a pivot parallel with the long axis of the casing. Obviously it might be hinged along an axis perpendicu- 55 lar to the long axis of the casing.

The entire cylinder is provided with a

cork, rubber or other suitable, and prefer- ably compressible lining G and the gate is similarly lined, it being understood that by such lining or by any other suitable means, 60 the entire cylinder is made relatively air tight so that the fumes of the disinfectant are entirely confined and cannot escape either through the interstices of the remov- 65 able cap at the bottom or through the gate at the top or through the aperture E¹ through which the shaft of the hand piece passes.

H is any suitable lid or gate which may be snapped over the top of the casing when 70 it is removed from the dental engine to prevent the escape of the disinfectant fumes.

It will be realized that while I have shown an operative device, many changes 75 might be made in the shape, proportion and material, and in the number and disposition of parts without departing from the spirit of my invention. The casing may be of metal with a cork or a rubber or fibrous lining, or the entire device might be made 80 of hard rubber or of any suitable material adapted to resist the disinfectant fumes and the interstices may be provided with any suitable liner or packing to prevent the es- 85 cape of the disinfectant fumes.

The essential point of my invention is that I provide a substantially air tight cas- 90 ing which may be quickly mounted upon and quickly removed from the hand piece, and which incloses a sterilizing or disin- 90 fecting element.

I claim:

1. A sterilizer for dental hand pieces adapted to be secured to the hand piece while it is secured to a dental engine, com- 95 prising a casing adapted to enclose the hand piece and having a gate arranged to open the casing to permit the hand piece to be inserted within the casing and to close against the hand piece after it has been so 100 inserted, means for securing the gate in closed position, and a sterilizing agent confined within the casing.

2. A sterilizer for dental hand pieces adapted to be secured to the hand piece 105 while it is secured to a dental engine, com- prising a casing the interior diameter of which is substantially greater than the nor- mal diameter of the hand piece, the upper end of the casing being substantially con- 110stricted to approximately the normal di- ameter of the upper end of the hand piece,

and having a hinged portion to give entrance to the casing and adapted when closed to frictionally engage the hand piece and a sterilizing agent contained within the 5 casing.

3. In a sterilizer for dental hand pieces adapted to be secured thereto while the hand piece is secured to a dental engine, comprising an enclosing casing formed with an 10 opening adapted to permit the entrance of

the dental hand piece, and a hinged part adapted to close the said opening and engage the hand piece to maintain the casing closed thereon, and a sterilizing agent confined within the casing.

15

Signed at Chicago, county of Cook, and State of Illinois, this 30th day of March, 1923.

PETER J. L. NEMMERS.
